UNITED STATES PATENT OFFICE.

EMIL G. SAUER, OF RICHMOND HILL, NEW YORK, ASSIGNOR TO BIGELOW CARPET COMPANY, A CORPORATION OF MASSACHUSETTS.

DESIGN FOR A CARPET.

40,512.

Specification for Design.

Patented Feb. 15, 1910.

Application filed December 16, 1909. Serial No. 533,490. Term of patent 7 years.

To all whom it may concern:

Be it known that I, EMIL G. SAUER, a citizen of the United States, residing at Richmond Hill, in the county of Queens and State of New York, have invented a new, original, and ornamental Design for Carpets, of which the following is a specification, reference being had to the accompanying drawing, forming part thereof.

The figure is a plan view of a carpet, showing my new design.

I claim:

The ornamental design for a carpet as shown.

EMIL G. SAUER.
